F. DUTCHER.
WINDOW CONSTRUCTION.
APPLICATION FILED JULY 22, 1920.

1,387,479.

Patented Aug. 16, 1921.

UNITED STATES PATENT OFFICE.

FRANK DUTCHER, OF PHILADELPHIA, PENNSYLVANIA.

WINDOW CONSTRUCTION.

1,387,479.

Specification of Letters Patent. Patented Aug. 16, 1921.

Application filed July 22, 1920. Serial No. 398,193.

To all whom it may concern:

Be it known that FRANK DUTCHER, a citizen of the United States, residing at Philadelphia, in the county of Philadelphia and State of Pennsylvania, has invented 5 certain new and useful Improvements in Window Constructions, of which the following is a specification.

This invention relates to window construction, and has for its primary object to provide an efficiently operating arrangement of 10 a pair of self-balancing sashes in the window frame whereby the necessity of employing the usual sash weight may be avoided.

15 In the present improvement I propose to employ chains or equivalent non-stretchable, though flexible, elements for operatively connecting the sashes to each other at one of their ends which are slidably mounted 20 in the frame, the sashes being hingedly connected to each other at their other end, and means for automatically adjusting the chains in the relative angular movement of 25 the sashes as they are shifted vertically in the frame whereby binding of the chains will be entirely obviated while at the same time no slack can accumulate therein.

The invention also contemplates the provision of improved means for mounting the 30 sashes for sliding and pivotal movement in the window frame whereby the present improvement may be readily applied to a window frame and equipped with either single or double weather stripping for the sashes.

35 Generally, the invention comprehends a single pair of window sashes which may be easily and quickly adjusted in unison to provide ventilation at both the bottom and top of the window, and provides means 40 whereby the sashes will be securely retained in their closed positions against accidental opening movement by strong air drafts or from other causes.

45 And finally, it is my purpose to materially simplify window construction of the above type and thereby enable the same to be constructed and installed at comparatively small cost and maintained in operative condition without requiring frequent and more 50 or less expensive repairs.

With the above and other objects in view, the present invention consists in the provision of a window construction as characterized, and in the improved combination and 55 arrangement of the several parts thereof to be hereinafter more fully described, illus-

trated in the accompanying drawing, and subsequently incorporated in the subjoined claims.

In the drawing wherein I have illustrated 60 several practical and satisfactory embodiments of the invention, and in which similar reference characters designate corresponding parts throughout the several views:

Figure 1 is a vertical sectional view of a 65 window provided with the present invention showing the sashes in full lines in closed position and in dotted lines in an open position.

Fig. 2 is a vertical section through the 70 window frame, the sashes being removed therefrom.

Fig. 3 is an enlarged vertical section 75 through the top of the window frame, showing the sash in dotted lines and illustrating the guide means for the sash chain.

Fig. 4 is a transverse horizontal section through one side of the window frame and sash taken on the line 4—4 of Fig. 3.

Fig. 5 is a similar view illustrating a 80 modified form of the sliding pivot member for the sash used in connection with double weather-stripping.

Fig. 6 is a detail vertical section illustrating the operation of the latter form of 85 the invention, and

Fig. 7 is a detail perspective view of the slide member shown in Fig. 5.

Referring now more particularly to Figs. 1 to 4 inclusive of the drawing, 5 designates 90 the window frame which includes the usual top rail 6 and the bottom sill 7 connected by the vertical side bars or jambs 8. The latter are provided in their inner faces with the parallel longitudinally extending grooves or 95 channels 9 and 9', respectively, which extend substantially the entire length of the frame, as clearly shown in Fig. 2 of the drawing.

The upper and lower sashes designated 100 and 11, respectively, have their meeting rails 105 hingedly connected at the inner sides thereof as at 12, and when these sashes are in closed position within the window frame they are disposed in a common vertical plane. The top rail 6 of the frame may be provided with stop strips, as shown in dotted lines in Fig. 3, between which the upper sash is engaged when in its closed position.

In each end of the groove 9 a slide member 110 is loosely engaged for free vertical movement. Preferably each slide member is in the form of a light, hollow metal block of

elongated rectangular shape and is provided at one of its ends with a laterally projecting cylindrical pin or trunnion 14. The upper end of the upper sash 10 and the lower end 5 of the lower sash 11 are each provided in the vertical stiles thereof with sockets, indicated at 15 to receive the trunnions 14, whereby it will be understood that the sashes are connected to the slide members for swinging or 10 pivotal movement with respect thereto.

The grooves 9 and 9' in each side of the frame communicate with each other at the centers of the jambs 8, as shown at 16 and in the grooves 9' the sash connecting chains 15 17 are disposed for the upper portions of their length. These chains pass, around the vertically spaced sheaves or pulleys 18 which guide the lower portions of the chains in the grooves 9. The lower ends of the chains 20 have fixed connections to the slide members 13 for the lower sash. At their upper ends the chains extend through openings 19 in the top rail of the window frame through which they are guided by the wheels 20, and 25 then pass around the pulleys or sheaves 21 journaled in the housings 22 secured to the frame. The extremities of the chains are connected to the upper ends of rods 23 which are vertically movable through the 30 hollow blocks of the slide members 13 to which the upper sash is pivoted. The movement of these rods under the pull of the chains is yieldingly resisted by the springs 24 surrounding the lower ends of the rods 35 and bearing at their upper ends against the slide members. By adjusting the nuts 25, threaded upon the rods 23 the tension of the springs may be properly regulated.

From the above description, it will be 40 understood that when the hingedly connected sash rails are forced outwardly and the lower sash raised, the upper end of the upper sash will move downwardly in the frame to a like extent and the sashes will 45 assume an angular relation to each other and with respect to the frame as seen in Fig. 1 of the drawing. This ventilation will be had at both the top and bottom of the window. In closing the window the lower sash 50 is pulled downwardly and through the medium of the connecting chains 17 the upper sash is moved upwardly so that the change in the angular relation of the sashes with respect to the frame will be uniform as they 55 move to a perpendicular position. As the slide members 13 gradually move apart and the hinge 12 approaches a position in line with the pivot trunnions 14 in the closing movement of the sashes, the chains 17 will 60 pull upon the rods 23 and thereby compress the springs 24. It will thus be seen that the yieldable connections between the chains and the upper sash eliminate all possibility of binding of the chains during the opening or 65 closing movements of the sashes. Further-

more, the sashes will be held tightly closed against strong air drafts from within the room when they are not positively locked, or prevented from accidental opening movement through other causes. In other words, 70 the chains will at all times be held perfectly taut and are therefore not subject to the inherent tendency to stretch to an objectionable extent which is a well known characteristic of the ordinary sash cord commonly 75 employed for this purpose.

In the adaptation of the invention above referred to, a single weather strip 26 is secured to each of the frame jambs at the inner sides of the sashes and the trunnions 80 14 are arranged in line with the grooves 9. However, when double weather stripping is used this arrangement of the trunnions is not permissible. In such case the grooves 9 and 9' are not provided and slide members of 85 the form shown in Figs. 5 and 7 are employed. Each slide member consists of a channel-shaped casting 27 having a flange 28 extending laterally from one edge thereof and carrying at its upper end the pivot pin or 90 trunnion 29. To the sash stile a wear plate 30 is secured and is provided with an opening 31 coinciding with the socket in the stile to receive the trunnion. The channel casting slides between the longitudinal stop 32 fixed 95 in the frame jamb and the guide cleat 33 secured upon the inner face of the jamb. The weather strip 26' is secured to the cleat 33 at the inner sides of the sashes. A second weather strip 34 is secured to the outer edge 100 of the sash stile and coats with the stop 32 when the sash is closed. It will be noted that the pivot or trunnion 29 in this construction of the slide member is disposed outwardly of the stop 32 and in line with the weather strip 105 34. Thus it will be apparent that when the sash is swung to open position, as in Fig. 6, the strip 34 will freely clear the stop 32 and will not bind thereon.

In both of the constructions above described the trunnion-receiving sockets in the sash stiles may be provided with fiber wear-resisting linings if desired, which will also render the device noiseless in its operation. The slide members 27 for the upper sash are 110 provided at the outer sides of their channel-shaped portions, and at the upper and lower ends thereof, with the inwardly projecting apertured lugs 35 to receive the yieldable chain-connecting rods 23 above referred to. It will of course be understood that the chain 115 extends through the channel portion of the slide member.

The present invention is primarily designed for use in connection with a single 120 pair of self-balancing weightless sashes but obviously it may also be applied and satisfactorily used in connection with a plurality of pairs of sashes, such for instance as are 125 illustrated, described, and claimed in Patent 130

No. 1,281,312, granted to me on October 15, 1918. Also it is to be understood that the present improvement is not to be limited to the particular type of chain herein illustrated as operatively connecting the sashes to each other since, obviously, other flexible though non-elastic connecting elements might be substituted therefor without materially affecting the practical efficiency of the invention.

Therefore, while I have herein shown and described several constructions which at the present time I believe to be entirely practical for the purpose in view, it is manifest that the essential features of the invention might also be incorporated in numerous alternative structural embodiments. Accordingly, I expressly reserve the privilege of adopting all such legitimate changes in the form, proportion, and relative arrangement of the several parts, as may be fairly considered within the spirit and scope of the invention as claimed.

What I claim is:—

1. The combination with a window frame, of a pair of sashes hingedly connected to each other at one of their ends, means for slidably and pivotally mounting the sashes at their other ends in the window frame for relative vertical movement, counterbalancing means common to both sashes to maintain the sashes in adjusted position, and a yieldable connection between said counterbalancing means and one of the sashes to permit of an independent movement of said means with respect to said sash in the movement of the sashes to open or closed position, said connection including an adjustable part movable relatively to the sash to control the effective operation of said counterbalancing means.

2. The combination with a window frame, of a pair of sashes hingedly connected to each other at one of their ends, means for slidably and pivotally mounting the sashes at their other ends in the window frame for relative vertical movement, a flexible, non-elastic counterbalancing element having a fixed connection to one sash, and means yieldably connecting said element to the other sash to permit of an independent movement of said element with respect to said sash in the movement of said sashes to open

or closed position, said means including a rod adjustable with respect to the sash and to which said counterbalancing element is connected.

3. The combination with a window frame, of a pair of sashes hingedly connected to each other at one of their ends, slide members vertically movable in the frame and having trunnions upon which the sashes are pivotally mounted at their other ends, flexible counterbalancing elements mounted in the frame and having fixed connections at one of their ends to the slide members for one sash, and yieldable means connecting said elements at their other ends to the slide members for the other sash, each of said yieldable means including a rod adjustably mounted in the slide member and to which the flexible element is connected.

4. The combination with a window frame, of a pair of sashes hingedly connected to each other at one of their ends, slide members vertically movable in the frame and having trunnions upon which the sashes are pivotally mounted at their other ends, flexible counterbalancing elements mounted in the frame and having fixed connections at one of their ends to the slide members for one sash, and yieldingly held rods carried by the slide members for the other sash and longitudinally movable with respect thereto to which the other ends of said counterbalancing elements are connected.

5. The combination with a window frame having a longitudinal stop secured in each side thereof and a longitudinal weather strip in spaced relation to each of said stops, of a pair of sashes hingedly connected to each other at one of their ends, a weather strip secured to each of the side edges of each sash and coacting with the outer sides of the stops, slide members each having a channel portion movable along the inner side of the stop at one side of the frame, and an outwardly projecting flange having a pivot trunnion upon which one of the sashes is mounted at its other end for swinging movement, said trunnions being located outwardly of the stops and in line with the weather strips on the sashes.

In testimony whereof I affix my signature.

FRANK DUTCHER.
